DISPLAY CARD AND FASTENER HOLDER

John J. Murphy, Oakville, and Alouis J. Reisinger, Waterbury, Conn., assignors to The Autoyre Company, Incorporated, Oakville, Conn., a corporation of Connecticut

Application September 17, 1941, Serial No. 411,096

17 Claims. (Cl. 206—47)

This invention relates to combined display cards and fastener holders, more particularly to display card means for maintaining screws, nails, or other fastener means in association with articles of manufacture on display, the screws, nails, or other fasteners being intended for use with the articles after the same have been sold, and the invention has for an object the provision of improved means of this character.

In the merchandising of various articles of manufacture, such for example as towel bars, soap dishes, tumbler holders and many other articles which in use are intended to be secured to a support by screws, nails, or similar fastener means, it is necessary in order to prevent customer dissatisfaction to supply with each article the proper number of screws or fasteners of the proper size, and difficulties have been encountered in this connection due to the tendency of the screws or fasteners to become lost or misplaced during the packing and shipping of the articles to the wholesaler, jobber, or retailer, and during the display of the articles by the retailer.

In many cases the retail merchandiser has in fact found it necessary to keep available at the sales counters a stock of screws or other fasteners so that the sales person may supply each purchaser with the necessary number of such screws or fasteners. This procedure is of course very unsatisfactory not only because of the necessity for maintaining a separate stock of such screws or fasteners, but also because of the tendency of the sales person to forget entirely or to include too few of the screws or fasteners, and because in many cases the screws or fasteners thus supplied will be of the wrong size.

In various attempts to solve this problem of supplying with each article sold the desired number of screws of the proper size, it has been proposed to support the screws on a display card attached to the article, but in all such prior attempts the screws or fasteners have been so associated with the display card as to expose the sharp points and the threads of the shanks of the screws or fasteners, whereby injury to the prospective customers or other handlers of the article, or damage to other articles by scratching during packing, shipping and handling, may result. Furthermore, it has been found that when so supported the screws and fasteners may work loose from the display card and be lost. Accordingly, it is a further object of this invention to provide a simple and inexpensive display card and fastener holder for maintaining the fasteners in association with the articles with which they are

subsequently to be used, which positively secures the fasteners against displacement or loss, which conceals and protects the shank portions of the fasteners from contact with the hands of persons examining or handling the articles and from scratching contact with other articles, which renders the fasteners readily available for use by removal of the display card from the article, and which may quickly and economically be associated with the articles to provide display surfaces carrying descriptive or explanatory indicia relative to the article and its use.

In carrying out the invention in one form, a sheet-like blank or body of relatively rigid material, such as cardboard or the like, is provided which may be attached to the article, and which includes an angularly extending tab portion through which the fasteners extend with the heads of the fasteners confined between the tab portion and a juxtaposed surface of the article itself. More particularly, a medial portion of the blank or body is cut out to form the tab, and the portions of the blank on opposite sides of this medial portion are folded about a bar-like portion of the article to provide front and rear display portions. The tab is folded out of the plane of the display portions so as to extend therebetween beneath the bar, whereby the screws or similar headed fasteners which extend through the tab are supported with the shanks thereof confined between the front and rear portions, and with the heads thereof confined between the tab and the bar positively to prevent displacement of the fasteners, the heads of the fasteners being visible through the cut-out portion so that the prospective purchaser may readily observe that the desired number of fasteners are included with the article being purchased.

For a more complete understanding of the invention, reference should now be had to the drawings in which:

Fig. 1 is a perspective view of a towel bar or similar article having a combined display card and fastener holder embodying the present invention applied thereto;

Fig. 2 is a fragmentary front elevational view of the towel bar and the display card and fastener holder of Fig. 1 with a portion broken away more clearly to illustrate the construction;

Fig. 3 is an elevational sectional view taken along the line 3—3 of Fig. 2;

Fig. 4 is a plan view of the blank or body portion from which the display card and fastener holder of Figs. 1, 2, and 3 is formed;

Fig. 5 is a fragmentary perspective view of

another form of towel bar having a modified form of display card and fastener holder applied thereto;

Fig. 6 is a top plan view of a corner towel bar or similar article having a modified form of display card and fastener holder embodying this invention applied thereto;

Fig. 7 is a fragmentary view similar to Fig. 6 showing the display card and fastener holder of Fig. 6 partially opened up, more clearly to illustrate the detailed construction thereof; and

Fig. 8 is a detail sectional view taken along the line 8—8 of Fig. 6.

Referring first to the embodiment of the invention illustrated in Figs. 1 to 4, inclusive, the invention is shown as embodied in a combined display card and fastener holder 10 which is applied to a towel bar of the type comprising a plurality of U-shaped bars 11 secured at their opposite ends to supporting brackets 12, the brackets including suitable apertures 13 by means of which the towel bar may be secured to a wall or other support by screws or similar fastener means 14, which screws or fastener means are shown as being carried by the combined display cards and fastener holders 10. Each of the fastener holders 10 is arranged to carry two screws, but it will of course be understood that each fastener holder may be arranged to carry as many screws or similar fasteners as are necessary to secure the towel bar or other article to the support.

Each of the fastener holders 10, as shown in Fig. 4, is formed from a substantially rectangular blank or body of relatively rigid sheet-like material, such as cardboard or the like, and is slit at a medial portion thereof along the lines 15, 16, and 17 to provide a tab portion 20 which may be bent out of the plane of the blank along the line 18 to form an aperture 19. The aperture 19, as shown, divides the blank or body portion into a front portion 21 and a rear portion 22 which are connected together by the strap-like portions 23 on opposite sides of the aperture 19. Preferably, the tab 20 is scored along the line 25 to divide the tab into two foldable portions 26 and 27, the portion 26 being provided with screw- or fastener-receiving apertures preferably formed, as shown, by the crossed slits 28, which provide, when the screws are inserted therethrough, four small tabs that tend to retain the screws or fasteners in the apertures by friction or by engagement with the threads on the screws.

In order to apply the display card and fastener holder 10 to an article such as the towel bar of Fig. 1, it is necessary only to insert the screws or fasteners 14 through the apertures provided by the crossed slits 28 in the tab portion 26 and to fold the strap portions 23 of the blank or body portion about the bar 11, as shown in Figs. 2 and 3, so as to bring the front and rear portions 21 and 22 into substantially face-to-face relation, the tab 20 being folded inwardly and downwardly, as shown best in Fig. 3, so that the portion 26 thereof extends beneath the bar 11 in spaced juxtaposed relation therewith and the portion 27 of the tab is tucked downwardly along the inner surface of the front portion 21. The front and rear portions 21 and 22 may then be secured together in any desired manner, but this securing is preferably accomplished simply by the use of a clip or staple 29 of the type which may readily be applied by clipping or stapling machines readily available on the market.

When the combined display card and fastener

holder 10 has been applied to the towel bar or other article in the manner above described, it will be seen that the screws or fasteners 14 are supported with the shank portions thereof confined between the front and rear portions 21 and 22 respectively, and with the head portions thereof confined between the tab portion 26 and an adjacent surface of the juxtaposed bar 11. Thus displacement or loss of the screws 14 from the tab portion 26 is positively prevented, and at the same time these screws are rendered readily available for use merely by removing the staple 29 or tearing the card so as to permit unfolding of the display card from about the towel bar.

The outer surfaces of both the front and the rear portions 21 and 22 are of course available for descriptive or illustrative indicia which may set forth the desirable characteristics of the towel bar or other article which is being displayed, and it will be noted that the heads of the screws 14 are at all times visible through the aperture 19 in the display card, so that the customer may be apprised of the fact that he is receiving the desired number of screws or fasteners. Confinement of the shank portions of the screws 14 between the front and rear portions of the display card is of particular importance in that it prevents scratching of adjacent articles during packing, shipping and display, and in addition prevents injury to the hands of a prospective purchaser or other handler of the towel bar.

In Fig. 5 a combined display card and fastener holder 10a is shown as applied to a conventional towel bar having a single bar 11a supported at its ends on brackets 12a, each of the brackets being of the type having two fastener-receiving apertures 13a, whereby four screws or like fasteners are necessary to secure the towel bar to a support. Accordingly, the fastener holder 10a, which is otherwise similar to the fastener holder 10 of Figs. 1 to 4, is provided with four fastener-receiving apertures in the tab corresponding to the tab 20 of Figs. 1 to 4 so that four screws or similar fasteners 14 are carried thereby.

In the embodiment shown in Figs. 6, 7, and 8, the towel bar or similar article is provided with a bar portion 30 which is bent to provide sections extending substantially at right angles to each other, and the display card and fastener holder 50 which is applied thereto comprises a substantially triangular rear or body portion 31 (Fig. 7) having wing portions 33 extending from the edges thereof, and connected to the body portion 31 by strap-like portions 34, the strap-like portions 55 being separated by medial apertures 35 correspond to the aperture 19 of the embodiment shown in Figs. 1 to 4. Extending from one edge of each of the apertures 35 is a screw or fastener supporting tab 36 which may, if desired, be identical with the tab 20 of the previously described embodiment but which, for the reasons herein-after set forth, are preferably of less length than the apertures 35 and provided with tapered end portions.

The wing portions 33 are adapted to be brought into overlying relation with the rear or body portion 31 by folding the strap portions 34 about the right angularly disposed sections of the bar 30, and the wing portions are preferably so shaped as to overlap each other. During the folding of the wing portions about the bar 30 the tab portions 36 are folded beneath the bar 30 and the tapered ends thereof are inserted through the opposite end of the slots 35 so that the tabs 36 rest on the edges 35a of the slots 35 with the tapered end

portion thereof lying along the outer faces of the wing portions. This inter-relation of the tabs and wing portions not only serves to hold the heads of the screws or fasteners 14 against the bar 30, but also assists in maintaining the wing portions 33 in their respective folded positions.

In order to provide a finished and pleasing appearance to the display card and fastener holder illustrated in Figs. 6 to 8, inclusive, the lower edge of the rear or body portion 31 is provided with an extending complementary portion 37 which is foldable along the line 38 so as to overlie the wing portions 33. After the complementary portion 37 has been folded upwardly to the position shown in Fig. 6, the rear portion 31, the wing portions 33, and the complementary portion 37 may all be secured together by a single staple or clip 39.

Preferably, the complementary portion 37 is provided with notches 40 along the edges thereof, which notches coincide with the adjacent edges of the apertures 35 to insure that the heads of the screws 14 will be clearly visible after the display card and fastener holder has been assembled on the corner towel bar. In this embodiment of the invention it will be noted that the lower edge formed by the fold-line 38 is sealed so that the sharp points on the shanks of the fasteners are rendered completely inaccessible, further to prevent the possibility of injury to persons handling the corner towel bar or to other towel bars during packing, shipping, or displaying of the same.

When the combined display cards and fastener holders heretofore described are made from relatively rigid material, and particularly when they are to be applied to square, edgewise disposed bars, such as the bars 11 and 30, it may be desirable to provide score lines, such as the lines 41 in Fig 4 or the lines 42 in Fig. 7, in order to insure proper folding of the strap-like portions 23 and 34 about the bars 11 and 30 respectively. Such score lines may of course be omitted if more flexible materials are used, and particularly if the display card and fastener holder is to be applied to a round or similarly shaped smooth bar.

It will now be apparent that this invention provides a display card and fastener holder which may be formed from a single sheet of material, and which may quickly and easily be applied to the desired article so as to associate with the article the desired number of screw or similar fasteners, the screw or similar fasteners being so supported as positively to insure against displacement or loss thereof while protecting other similar articles and persons handling the article from injury or scratching upon contact with the screw threads or other sharp points on the said screws or fasteners.

While particular embodiments of the invention have been shown, it will be understood, of course, that the invention is not limited thereto, since many modifications may be made, and it is therefore contemplated by the appended claims to cover any such modifications as fall within the true spirit and scope of the invention.

Having thus described our invention, what we claim and desire to secure by Letters Patent is:

1. A combined display card and fastener holder for an article of manufacture of the type adapted to be secured to a support by separate fastening means, comprising a sheet-like display portion and a fastener-holding portion, said display portion including a section attachable to said article, said fastener-holding portion being adapted to

extend angularly from said display portion in spaced relation to said attachable section so that upon attachment of said section to said article said holding portion underlies a portion of said article in spaced juxtaposition with a portion of said article, said holding portion supporting the fastener means between said holding portion and said article in engagement with said article.

2. A combined display card and fastener holder for an article of manufacture adapted to be secured to a support by headed fastener means, comprising a sheet-like display portion and a fastener-holding portion, said display portion including a section attachable to said article, said fastener-holding portion being adapted to extend angularly from said display portion in spaced relation to said attachable section so that upon attachment of said section to said article said holding portion underlies a portion of said article in spaced juxtaposition with a portion of said article, said holding portion supporting headed fastener means extending through said holding portion with the head thereof confined between said holding portion and said juxtaposed portion of said article whereby said portion of said article prevents displacement of said fastener means from said holding portion, said display portion having an opening adjacent said holding portion for rendering the head of said fastening means visible in its confined position.

3. A combined display card and fastener holder for an article of manufacture of the type adapted to be secured to a support by separate fastener means, comprising a sheet-like display portion and a tab portion bendable out of the plane of said display portion, said display portion having a section attachable to said article, said tab portion when bent out of the plane of said display portion extending in spaced relation to said attachable section to underlie a portion of said article in spaced juxtaposed relation thereto upon attachment of said section to said article for supporting fastener means therebetween in position-maintaining contact with said tab portion and said portion of said article, said display portion having an opening therein adjacent said tab portion for rendering said fastener means visible in its supported position.

4. A combined display card and fastener holder for an article of manufacture of the type adapted to be secured to a support by headed fastener means, comprising a sheet-like display portion including a section attachable to said article, and a tab portion bendable out of the plane of said display portion in spaced relation to said section upon attachment of said section to said article to underlie a portion of said article, said tab portion having a fastener receiving aperture for supporting a fastener with one surface of the head thereof contacting a surface of said tab and an opposite surface of said head contacting said article portion.

5. A combined display card and fastener holder for an article of manufacture of the type adapted to be secured to a support by headed fastener means and having a bar-like portion, comprising a sheet-like body portion including a section foldable about said bar-like portion to provide front and rear portions, and a portion adapted to extend between said front and rear portions in spaced relation to said foldable section upon folding of said section about said bar-like portion, whereby said last mentioned portion extends in spaced juxtaposition to said bar-like portion for supporting a headed fastener extending there-

through with the head of said fastener confined between said extending portion and said bar-like portion.

6. A combined display card and fastener holder for an article of manufacture of the type adapted to be secured to a support by headed fastener means and having a bar-like portion, comprising a sheet-like display card including a section foldable about said bar-like portion to form said card into a front portion and a rear portion, said foldable section being slit to form a tab integral with one of said front and rear portions and bendable to extend therebetween upon folding of said foldable section about said bar-like portion, whereby said tab extends beneath said bar-like portion and tab upon the extension of headed fastener means therethrough supports said fastener means with the head thereof confined between said bar-like portion and said tab and with the shank portion of said fastener means confined between said front and rear portions.

7. The combination with an article of manufacture of the type adapted to be secured to a support by headed fastener means and having a bar-like portion, of a combined display card and fastener holder comprising a sheet-like body portion foldable about said bar-like portion to provide front and rear portions, a portion extending between said front and rear portions in spaced juxtaposition to said bar-like portion for supporting a headed fastener extending therethrough with the head of said fastener confined between said extending portion and said bar-like portion, and means for securing said front and rear portions together to retain said display card and fastener holder on said article.

8. The combination with an article of manufacture of the type adapted to be secured to a support by headed fastener means and having a bar-like portion, of a combined display card and fastener holder comprising a sheet-like display card folded about said bar-like portion to form a front portion and a rear portion, a section of the folded portion being slit to form a tab integral with one of said front and rear portions and extending therebetween beneath said bar-like portion, said tab upon the extension of headed fastener means therethrough supporting said fastener means with the head thereof confined between said bar-like portion and said tab and with the shank portion of said fastener means confined between said front and rear portions, and means for securing said front and rear portions together in face-to-face relation at a point remote from said bar-like portion to retain said display card and fastener holder on said article.

9. A combined display card and fastener holder for an article of manufacture having angularly extending bars and being adapted for securement to a support by separate fastener means, comprising a sheet-like body portion having edges extending at an angle substantially equal to the angle between said bars, wing portions extending from said edges including a section foldable about the respective adjacent bars to cause said wing portion to overlie one surface of said body portion, and a fastener holding portion adapted to extend angularly from the plane of one of said portions in spaced relation to said foldable section upon folding of said section about said bars, whereby said fastener holding portion extends in spaced juxtaposition to one of said bars, said fastener holding portion having fastener means extending therethrough and engaging said

juxtaposed bar to prevent displacement of said fastener means from said holding portion.

10. A combined display card and fastener holder for an article of manufacture having angularly extending bars and being adapted for securement to a support by separate fastener means, comprising a sheet-like body portion having edges extending at an angle substantially equal to the angle between said bars, wing portions extending from said edges including sections foldable about the respective adjacent bars to cause said wing portions to overlie one surface of said body portion, a tab portion bendable to extend between said body portion and said overlying wing portions in spaced relation to said foldable sections upon folding of said sections, whereby said tab portion extends in juxtaposed relation to one of said bars, said tab portion being apertured to receive the shank of a headed fastener for supporting said fastener with the head thereof confined between said tab portion and said one bar and the shank thereof confined between said body and wing portions.

11. A combined display card and fastener holder for an article of manufacture having angularly extending bars and being adapted for securement to a support by separate fastener means, comprising a sheet-like body portion having edges extending at an angle substantially equal to the angle between said bars, wing portions extending from said edges including sections foldable about the respective adjacent bars to cause said wing portions to overlie one surface of said body portion, a fastener holding portion adapted to extend angularly from the plane of one of said portions in spaced relation to said foldable sections upon folding of said sections about said bars, whereby said holding portion extends in spaced juxtaposition to one of said bars, said holding portion having fastener means extending therethrough and engaging said juxtaposed bar to prevent displacement of said fastener means from said holding portion, and a complementary portion extending from another edge of said body portion foldable over said wing portions to provide a display surface.

12. In combination with an article of manufacture having angularly extending bars and being adapted for securement to a support by separate fastener means, of a combined display card and fastener holder comprising a sheet-like body portion having edges extending substantially parallel to said bars, wing portions extending from said edges folded about the respective adjacent bars to overlie one surface of said body portion, and a fastener holding portion extending angularly from the plane of one of said portions in spaced juxtaposition to one of said bars having fastener means extending therethrough, said juxtaposed bar preventing displacement of said fastener means from said holding portion, a complementary portion extending from another edge of said body portion foldable over said wing portions to provide a continuous display surface, and means securing said body portion, wing portions, and complementary portions in said overlying relation.

13. The combination with an article of manufacture securable to a support by headed fastener means and having a bar-like portion, of a combined display card and fastener holder comprising a sheet of foldable material having an aperture in a medial portion thereof dividing said sheet into opposed portions connected by spaced strap portions, said strap portions being folded

about said bar-like portion to position said opposed portions in face-to-face relation, a tab portion extending angularly from one edge of said aperture in spaced juxtaposed relation to a surface of said bar-like portion not encircled by said strap portions for supporting headed fasteners extending therethrough with the heads of said fasteners confined between said tab portion and said juxtaposed surface and exposed to view through said aperture.

14. The combination with an article of manufacture securable to a support by headed fastener means and having a bar-like portion, of a combined display card and fastener holder comprising a sheet of foldable material having an aperture in a medial portion thereof dividing said sheet into opposed portions connected by spaced strap portions, said strap portions being folded about said bar-like portion to position said opposed portions in face-to-face relation, a tab portion integral with one of said opposed portions extending from one edge of said aperture across the space between said opposed portions and in spaced relation to said bar-like portion, said tab portion supporting a fastener extending therethrough with the shank of said fastener hidden from view between said opposed portions and with the head of said fastener confined between said tab portion and said bar-like portion exposed to view through said aperture.

15. The combination with an article of manufacture securable to a support by headed fastener means and having a bar-like portion, of a combined display card and fastener holder comprising a sheet of foldable material having an aperture in a medial portion thereof dividing said sheet into opposed portions connected by spaced strap portions, said strap portions being folded about said bar-like portion to position said opposed portions in face-to-face relation, a tab portion integral with one of said opposed portions extending from one edge of said aperture across the space between said opposed portions and in spaced relation to said bar-like portion, said tab portion supporting a fastener extending therethrough with the shank of said fastener hidden from view between said opposed portions and with the head of said fastener confined between said tab portion and said bar-like portion exposed to view through said aperture, and means for securing said opposed portions together in

said face-to-face relation at a point remote from said bar-like member.

16. The combination with a towel bar having bar portions extending at substantially a right angle to each other, of a combined display card and fastener holder comprising a sheet of foldable material including a substantially triangular body portion and wing portions respectively connected to two edges of said body portion by spaced apart strap portions, said strap portions being folded about said bar portions partially to encircle the same and to position said wing portions in overlying relation to said body portion, tab portions extending transversely from said edges of said body portion between said spaced apart strap portions in spaced relation to said bar-like portions for supporting headed fasteners with the shanks thereof extending through said tab portions between said overlying portions and with the heads thereof confined between said tab portions and said bar-like portions, and means for securing said wing portions and said body portion together in said overlying relation.

17. The combination with a towel bar having bar portions extending at substantially a right angle to each other, of a combined display card and fastener holder comprising a sheet of foldable material including a substantially triangular body portion and wing portions respectively connected to two edges of said body portion by spaced apart strap portions, said strap portions being folded about said bar portions partially to encircle the same and to position said wing portions in overlying relation to said body portion, tab portions extending transversely from said edges of said body portion between said spaced apart strap portions in spaced relation to said bar-like portions for supporting headed fasteners with the shanks thereof extending through said tab portions between said overlying portions and with the heads thereof confined between said tab portions and said bar-like portions, a complementary substantially triangular portion extending from the third edge of said body portion and folded along the line of juncture therewith to overlie said wing portions, and a staple-like member securing said body, wing and complementary portions together in said overlying relation.
